DESIGN FOR A LUMINAIRE

Carl F. Haas and Elroy W. Yungman, Cleveland,
Ohio, assignors to Westinghouse Electric &
Manufacturing Company, a corporation of
Pennsylvania

Application May 13, 1942, Serial No. 106,884

Term of patent 14 years

To all whom it may concern:

Be it known that we, Carl F. Haas and Elroy W. Yungman, citizens of the United States, residing at Cleveland, in the county of Cuyahoga and State of Ohio, have invented a new, original, and ornamental Design for a Luminaire, of which the following is a specification, reference being had to the accompanying drawing, forming a part thereof, in which:

Figure 1 is a perspective view of a luminaire embodying our new design;

Fig. 2 is an enlarged end elevational view thereof;

Fig. 3 is an enlarged side elevational view of the end thereof; and

Fig. 4 is an enlarged side elevational view of a portion thereof.

Figs. 2 and 3 show in more detail than Fig. 1 the opposite ends of the luminaire of Fig. 1, which shows a multi-section luminaire, the end section shown broken being the same in appearance as that shown in full.

We claim:

The ornamental design for a luminaire, as shown and described.
